UNITED STATES PATENT OFFICE.

CROMER HOFFMAN, OF MECHANICSVILLE, NEW YORK.

NOTE-REGISTER.

1,224,170.

Specification of Letters Patent.

Patented May 1, 1917.

Application filed May 18, 1916. Serial No. 98,408.

To all whom it may concern:

Be it known that I, CROMER HOFFMAN, a citizen of the United States, residing at Mechanicsville, county of Saratoga, and State 5 of New York, have invented certain new and useful Improvements in Note-Registers, of which the following is a specification.

This invention relates to note registers.

My object is to provide a combined note 10 register and "tickler" which will enable banks and other financial institutions to quickly and completely classify and digest and readily refer to all necessary information regarding notes and discounted paper 15 handled.

My invention is based, generally speaking, on an improved register and tickler which provides for the abstracting of the particulars of notes or other paper at the 20 place of credit entry, that is, at the place where the note is recorded corresponding to its maturity or due date as contradistinguished from those methods or registers which contemplate the identification of notes 25 or paper in reference to the place of debit entry or date of discount. Consequently, the particulars of a given note or paper appear at the date corresponding to the due date or maturity date which is the important 30 date to be kept track of both by the bank and any party interested in, or liable on, the note.

In carrying out the invention, cards or 35 sheets are used, and preferably, separate cards in a card case or cabinet to enable the sheets bearing the information to be readily removed from the file or cabinet at any time and also to enable several persons to use the same register. I am aware, however, that 40 my invention is not restricted to embodiment in card form, as it might be carried out in loose leaf form, and I do not, therefore, thus limit myself.

The sheet or card used is of improved 45 form so that it is self-identifying with its proper position in the register. The guides and the cards are provided with indicia by which the cards may be quickly referred to to obtain the information appearing there- 50 on and, when removed from the file, may be readily restored to their proper position with little likelihood of error.

Preferably, the upper and lower edges of 55 the cards are both of the same improved form, in tabbed construction so that they are reversible and, whichever edge is up-

permost, will afford all of the advantages hereinafter specified and also provide for the use of both sides thereof for the abstracting of the information. 60

As the cards of my register and tickler contain information abstracted from the notes, and are arranged according to the due or maturity dates of the notes, should an inquiry be made by a maker, indorser, 65 payee, or other interested party, or by the bank, as to when a particular note is due, or as to any other information with respect to that note, it will be necessary to use in conjunction with my register and tickler an 70 index under which the notes are classified alphabetically. Such an index may be a special one on cards arranged under alphabetical guides and containing any desired 75 information with respect to the notes, or, the notes themselves may be filled alphabetically in any suitable alphabetical index so that they are self-indexing.

In my improved register and tickler constituting the present invention, I do not 80 herein set forth any particular alphabetical index nor limit myself to the use of any such index and leave this to the user according to preferences.

The manner of using the register and 85 tickler is set forth at length hereinafter in connection with the embodiment of the invention which is shown in the accompanying drawings, in which—

Figure 1 is a perspective of the register 90 and tickler;

Fig. 2, a view of the front of an abstract card; and

Fig. 3, a similar view of a "demand" card. 95 The register and tickler has twelve guide cards 1 provided with a tab 2, located, preferably, at the left-hand upper corner thereof and bearing the indicia 3 which, on the first card, will be "—1— January;" on the second card "—2— February;" on the third card "—3— March," etc. In addition I may provide a guide card 4 having a tab provided with the word "Demand" and another guide card 5 whose tab is provided with the words "Long term." 100 105

For each month thus indicated by the guide cards 1, I provide thirty-one, or less, abstract cards 6, one side of which is shown in Fig. 2. These abstract cards are provided with tabs 7 and 8 at their upper left-hand and upper right-hand corners and corresponding tabs 9 and 10 at their other cor- 110

ners. The tab 7 will be provided with the numeral corresponding to the number of the month. For instance, the card illustrated in Fig. 2 bears the numeral "5" on the tab 7, thus indicating that it is a card which belongs to the month of May. The tab 8 bears the month and year thus: May 1916. The tabs 9 and 10 are, on their reverse sides, provided with the numeral "5" and the words and numbers "May 1916" corresponding to the indicia on tabs 7 and 8, and consequently, whichever edge of the card is filed uppermost, the month identifying indicia will appear.

15 The upper and lower edges of the card are provided with date tabs 11 and 12. The cards shown in Fig. 2, being for an abstract of notes having a maturity of May 10, the tabs 11 and 12 will bear the numeral "10."

20 Beginning with the first card which represents the first day of the month, the tabs 11 and 12 of successive cards 6 bear numerals "1," "2," "3," "4," etc., up to "15" for the first series and for the second series "16" to 25 "31," the tabs 11 and 12 of the respective cards being so cut that they are successively arranged in a row so that each tab is visible.

A preferred arrangement of columns and headings for an abstract card 6 is shown in 30 Fig. 2, the opposite side of the card being identical with the side shown. The columns are provided with horizontal lines 13 which may run from "1" to "20" on one side of the card and are correspondingly numbered 35 at the left-hand side thereof as at 14, and on the opposite side of the card they may run from "21" to "40" and be correspondingly numbered so that both sides of the card may be used and each card will then 40 be adapted to accommodate abstracted or digested information pertaining to all essential particulars of forty different notes, or a lesser number, falling due, or intended for notification, on the date represented by 45 the card. For instance, the card shown in Fig. 2 is adapted to accommodate abstracted data pertaining to notes falling due on May 10, 1916. Additional cards may be used for each day or any particular day, all of said 50 cards having their tabs 11 and 12 in the same position and the cards then being filed one back of the other. Successive cards, after the first, will bear numbering 41—60 on one side and 61—80 on the other side and 55 a third card would have correspondingly higher numbers.

The columns, from left to right, of a card 6, are headed "When disc"; "Date of item"; "Time"; "Discount"; "Interest"; 60 "Debit amount"; "Credit amount"; "Date forwarded or date of partial payment"; "Maker or payer"; "Endorser or for whose account"; "Where payable when and where sent"; "Secured by D 1 or more indiv. E 65 stocks & bonds F other personal security

G R. E. Mt'g, or lien on realty"; "List of notes disc to day number year due amount."

The columns at the right of the card headed "List of notes discounted to-day" as indicated at 15 are provided for the entry 70 of a debit record of the debited "loans" for that day after they have been abstracted on the cards corresponding to their due dates and the note numbers affixed. The column "Credit amount" as indicated at 15', provides for the entry of a credit record of the 75 credited "loans" for that day. Both debit and credit records and both total footings appear on the card for any day's business. The other columns provide for the recording 80 of security for the loan and all dates, discounts, interest and other particulars, including the date of discount of the note, required in usual banking practice.

In Fig. 3 there is shown a card 16 for use 85 in connection with the "demand" notes or loans. The cards 16 have columns and headings affording spaces for entry of all necessary matter in connection with a note or loan payable on demand, including the security, partial payments, parties and dates, the information being sufficiently full but not as detailed as necessary for the card 6. The "demand" cards 16 are numbered consecutively beginning with "1" as indicated 90 at 17 in the upper left-hand corner and on the upper right-hand corner there is the word "Demand." The horizontal lines or 95 rulings 18 are similar to those shown at 13 and are correspondingly indented by note numbers as in the column 19 at the left-hand end of the card.

Cards used in connection with the guide "Long term" indicated at 5 are similar to the cards 6, being marked with the number 100 of the month in the upper left-hand corner and the month and year of the due date in the upper right-hand corner.

With my register, instead of being registered in a group under the heading of the 110 date received, or date of discount as it is called, as is a common practice at the present time, notes are immediately abstracted or carried to the card 6 of the same date as the due dates of the notes and are 115 there registered or entered in detail, including the date of discount. For instance, all notes, regardless of date of discount, which mature or become due on May 10, 1916, are entered on the card shown in 120 Fig. 2 which represents all notes falling due May 10, 1916, and in the columns provided on the card there is entered all data pertaining to that particular note. Consequently, for May 10, 1916, on one or more 125 cards for that date, there appears a full record of all paper coming due that day.

The user can employ as an index either an alphabetical filing of the notes themselves or any other device.

In operation, the note book-keeper at the close of the day's business makes an adding machine total of the notes to be charged to loans and discounts and of the amounts of interest and discount to be credited to profit and loss provided he is making a debit operation. He then affixes the maturity on each note and sorts the notes in groups according to their dates of maturity. The next step 5 is to remove from the register tickler file the cards 6 for the same dates as the due or maturity dates on the notes just sorted and to proceed to enter on the cards 6 such information as is required. As each note is 10 entered on the card 6, the note itself is numbered as follows: Month No. —, tab No. —, line No. —.

As an example, suppose the card for May 10, 1916, is being used and the entry is on 20 line 19. The note would then be numbered 5—10—19, the first part of the number indicating the guide which would be the fifth month, or May; the second part of the number the tab on the card, which would be 25 the card corresponding to the tenth day of May, and the third part of the number, the line location on that card which would be line 19.

If the note to be entered is "on demand" 30 the entry is made on the first card 16 and first line thereof having available space. A demand note is then numbered by prefixing "D" to the number of the card and the number of the line. For example, referring to 35 Fig. 3, a demand note might be entered on card No. 4, line 26, and in that event, the note itself would be provided with the indicia "D—4—26."

If the note to be entered is not discounted 40 paper, but for collection account of another party, the entry should be made in a segregated position on the card corresponding to the due date and the note numbered the same as a discounted time note except the 45 prefix "C" should be used on the note and on the card. For example, if the note is due September 12, it might be provided with the following: "C—9—12—32" which would indicate collection paper, guide 9, tab No. 50 12, line No. 32, that is, the ninth month, 12th day of the month and line 32 of card for that date.

If the note to be entered is a "long term" 55 note, that is, if the period of time to run is more than one year, a card with a proper tab should be taken from the stock supply and the year and month of the due date of the note written in the upper right-hand corner and the number of the month in the 60 upper left-hand corner. The lines should be numbered beginning with "1" and the note abstracted and numbered in the same manner as if the card had been used in the "set up" portion of the file and it would then be 65 filed under guide card 5, "Long term." A

separate card for each different maturity date should be used for "long term" notes. The card is taken out and placed in its proper position in the current file at the proper time.

The bookkeeper may index the makers of the note and make a liability record of such persons or firms as required by the bank and this can be done from the abstract card or from the notes direct.

In a credit operation, at the close of the day, the note bookkeeper in like manner takes an adding machine total of the paid and renewed notes to be credited to loans and discounts and he again sorts his "credit loans" slips in groups according to maturities and takes from the file the cards 6 of corresponding dates. Where the notes are being credited that are due either before or after the date of any day's business, comparison should be made at the place of entry of such notes of the amount of credit with entry at time of registry and if correct, notation can be made there "Credited (date)." The amount to be credited, together with the note number and names of makers of such notes are brought forward to the cards for that day's business. Where notes are to be credited and are due on the date of credit, the amount is simply extended into "Cr." 95 column opposite "Dr." entry.

There should be a sufficient supply of "stock" cards for the register and tickler file tabbed from "1" to "31" inclusive and blank as to card number, date and line number so that where one or two cards are inadequate for the day's business, other cards with the same tab number for that day may be inserted and the same card number and date affixed as are on the cards for that date. 100 The line numbers of cards should in no event be duplicated, but should run consecutively regardless of how many cards are used for a given day.

With my invention, discounted paper, collection notes, accepted bills of exchange and other paper are handled with a single register and tickler file, in connection with any desired alphabetical indexing of the notes and paper, thus saving repetition of entries 110 and enabling all entries, inspections and operations to be simplified and the work minimized.

The registered positions of the notes are brought in harmony with the positions of the 120 notes themselves as kept in a bundle for each month, if thus arranged. Furthermore, when crediting "loans" for any day, observation and comparison may be made of the amount of any item with the amount as debited, as the tickler is the place of original entry; this prevents errors between the dates of note inventory and proof of loans. The numbering system assists in detecting entry 125 on a wrong card of the register and tickler 130

as a comparison of the note number with maturity date will enable one to tell at a glance if the note is entered in the proper place and if not, where it is entered.

- 5 In connection with demand paper, particularly, it is to be noted that no matter how long the note may be allowed to run after the date of discount, the data of same is as easily accessible as the record of any note 10 recently taken into account. Furthermore, the abstracting of data makes possible the easy compilation of information as required in the reports, from time to time, to the Comptroller of Currency. The reports call 15 for information of the ninety consecutive days following the "call." The information can be taken in groups from the ninety cards in consecutive order for that period.
- 20 The inversion of the place of registering makes one entry take the place of two and makes the particulars of notes of the same due dates easily accessible.

The method is responsive to the demands 25 of note book-keeping for by it when the maturity of a paper is sought, it is only necessary to find the name in the index (which may be of any preferred kind) and the number indicated on the index points definitely 30 to the card 6 by month and day of the month and line numbering to the place of registry of that note.

Having thus described my invention, what 35 I claim as new and desire to secure by Letters Patent, is:

1. A combined register and tickler for 40 notes and the like, comprising guides representing periods, such as months of the year, and abstract cards or sheets each having month or period identification indicia, day 45 indicia, columns for the entry of particulars concerning notes requiring attention on that date, and successive cross rulings for the columns which are provided with individual identifying indicia, whereby a plurality of notes or like paper requiring attention on a given date may all be abstracted on a card or cards for that date.

2. A combined register and tickler for 50 notes and the like, comprising monthly guides, abstract cards or sheets each having tabs provided with month identifying indicia, a tab bearing day of the month number, columns for the entry of particulars 55 concerning notes requiring attention on that date, and successive cross rulings for the columns which are provided with consecutive individual identifying numbers, whereby a plurality of notes or like paper requiring attention on a given date may all be abstracted on a card or cards for that date.

3. A combined register and tickler for 60 notes and the like, comprising guides each having a tab with the name of the month

and a number corresponding to the number 65 of the month, and abstract cards or sheets each having tabs provided with the name of the month and number of the month, and a tab bearing the date of the month, columns for the entry of particulars concerning notes 70 requiring attention on that date, and successive cross rulings for the columns which are provided with consecutive identifying numbers, whereby a plurality of notes or like paper requiring attention on a given 75 date may all be abstracted on a card or cards for that date.

4. A combined register and tickler for notes and the like, comprising guides having tabs provided with the names and numbers 80 of the months, reversible abstract cards or sheets each having on both filing edges two tabs, one bearing the number of the month and the other the name of the month and a third tab bearing the date of the month, columns on both sides of each card or sheet for the entry of particulars concerning notes requiring attention on that date, and successive cross rulings for the columns on both 85 sides of the card or sheet, said rulings being provided with consecutive numbers for purposes of line identification, whereby a plurality of notes or like paper requiring attention on a given date may all be abstracted on a card or cards for that date and each 90 card may be used with either edge exposed.

5. A combined register and tickler for notes and the like, comprising monthly guides and additional guides for "demand" and "long term" notes, abstract cards or 100 sheets representing days of the month, different sets being used for the different months represented by the monthly guides, each abstract card having month identification indicia, day identification indicia, columns for the entry of particulars concerning notes requiring attention on that date, and successive cross rulings for said columns which are provided with individual identifying indicia, corresponding abstract cards 105 arranged under the "Long term" guide, and "demand" abstract cards arranged under the "Demand" guide, the latter cards being numbered consecutively for primary identification under the "Demand" guide and provided with columns for the entry of particulars concerning notes requiring attention, and successive cross rulings for the columns, said cross rulings being provided with individual identifying indicia. 110

6. A card or sheet having tabs one of which is provided with the name of the month and the other with the number of the month, and a third tab provided with a number representing the day of the month. 115

7. A reversible card or sheet having on each of its opposite edges tabs, one of which is provided with the name of the month and

the other with the number of the month, and a third tab provided with a number representing the day of the month.

8. A card or sheet having two tabs, one bearing the month of the year and the other the number of the month, a third tab bearing the date of the month, columns on the

card for the entry of data, and cross rulings for said columns, said cross rulings having consecutive numbers for purposes of line 10 identification.

In testimony whereof, I hereunto affix my signature.

CROMER HOFFMAN.
